UNITED STATES PATENT OFFICE

ISABELLE SPOONEMORE, OF SAN DIEGO, CALIFORNIA

DESIGN FOR A CAP

Application filed May 10, 1929. Serial No. 31,171. Term of patent 3½ years.

To all whom it may concern:

Be it known that I, ISABELLE SPOONEMORE, a citizen of the United States, residing at San Diego, in the county of San Diego and State of California, have invented a new, original, and ornamental Design for a Cap, of which the following is a specification, reference being had to the accompanying drawing, forming part thereof.

The figure is a perspective view of the cap in position on the head of the wearer which latter is indicated in dotted lines, showing my new design.

I claim:

The ornamental design for a cap as shown.

ISABELLE SPOONEMORE.
